US00D968391S

(12) **United States Design Patent** (10) **Patent No.:** **US D968,391 S**
Wen et al. (45) **Date of Patent:** **** Nov. 1, 2022**

(54) **ELECTRONIC DEVICE**

(71) Applicant: **ASUSTeK COMPUTER INC.**, Taipei (TW)

(72) Inventors: **Chuan-Hao Wen**, Taipei (TW);
Liang-Jen Lin, Taipei (TW);
Hung-Chieh Wu, Taipei (TW);
Min-Chieh Yang, Taipei (TW);
Chung-Wei Wu, Taipei (TW)

(73) Assignee: **ASUSTeK COMPUTER INC.**, Taipei (TW)

(**) Term: **15 Years**

(21) Appl. No.: **29/654,839**

(22) Filed: **Jun. 28, 2018**

(51) LOC (13) Cl. **14-02**

(52) U.S. Cl.

USPC **D14/341**; D14/248

(57) **CLAIM**

The ornamental design for an electronic device, as shown and described.

DESCRIPTION

FIG. 1 is a perspective view of an electronic device showing a first embodiment of our new design;

FIG. 2 is a front view of the first embodiment;

FIG. 3 is a rear view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a perspective view of the electronic device showing a second embodiment of our new design;

FIG. 9 is a front view of the second embodiment;

FIG. 10 is a rear view of the second embodiment;

FIG. 11 is a left side view of the second embodiment;

FIG. 12 is a right side view of the second embodiment;

FIG. 13 is a top view of the second embodiment; and,

FIG. 14 is a bottom view of the second embodiment.

The dashed broken lines illustrate portions of the electronic device and form no part of the claimed design.

1 Claim, 10 Drawing Sheets
